CIRCULAR WARP KNITTING MACHINE

Max Richard Böhmer, Chemnitz, Germany, assignor to Internationaler Maratti Maschinenverkauf A.-G. Berlin, Berlin, Germany

Application March 26, 1934, Serial No. 717,510
In Germany April 7, 1933

3 Claims. (Cl. 66—5)

This invention relates to a circular warp knitting machine and its object is to facilitate the supervision of the machine, to eliminate vibration and noise, to avoid entanglement of threads, 5 and to simplify and generally improve the machine construction.

This object is achieved according to the invention by dividing the needles into two intercalating, separately operative groups, alternate 10 needles belonging to different groups.

With this arrangement the two groups of needles can be made to work either simultaneously but out of phase with each other or one after the other, and since the fabric will then be 15 either urged by the two groups in opposite directions or held down by one group while the other operates, the need for presser rings which cause a great deal of vibration and noise, or for web-holders which complicate the machine construction, will be eliminated. Besides, since only 20 half the number of needles are engaged in loop making at any particular time, the supervision of the machine will be easy, and since the spacing of the threads will be correspondingly doubled, entanglement of threads and the trouble 25 and waste of time accompanying such entanglement will be avoided.

Fig. 1 of the accompanying drawing represents a fragmentary sectional view of a knitting machine constructed according to the invention,

Fig. 2 is an elevation at right angles to Fig. 1,

Figs. 3—6 are diagrams illustrating the needle positions at different stages of the knitting operation,

Fig. 7 is a fragmentary sectional view of a machine of modified construction, and

Figs. 8—11 are diagrams illustrating the needle movements obtainable with the modified machine construction.

In the illustrated arrangements, the machine comprises a needle cylinder 9 having vertical tricks in which the knitting needles are slidably mounted in the usual manner. In Figs. 1 and 2 the needles are controlled and operated by rocking levers 10 and 11 which are fulcrumed on 40 pivots 12 carried by bearing brackets 16, the latter being mounted on a support 17 secured to the needle cylinder 9. There is one rocking lever for each needle, and the butts of the 45 needles engage in forks at the ends of the levers so that the rocking movement of the levers will result in an up and down movement of the needles. Levers 10 alternate with levers 11, the former being double-armed and the latter single- 50 armed. A vertically reciprocated operating ring

18 is provided with arms 13 and 15 secured to the ring by means of leads 14. The arms 13 engage the levers 10 pivotally at one side of the fulcrum 12, and the arms 15 engage the levers 11 in the same way but at the opposite side of the 5 fulcrum. The result of this arrangement is that one group of alternately arranged needles will be moved upwards while the other group is moved downwards by the operating ring 18.

Figs. 3—6 illustrate the needle movements relative to the cylinder trick wall 25 of the machine. Six consecutively numbered needles are shown in these figures, (eight needles in Fig. 2), the needles with odd numbers being operated by the levers 11 and those with even numbers, by the 10 levers 10. In Fig. 3 the needles with odd numbers are descending and the needles with even numbers are being raised by the downwardly moving operating ring 18. At a further stage of the movement, all the needles will be on a 20 level with one another, as shown in Fig. 4. At a still further stage, the needles with even numbers will be on a higher level than those with odd numbers, as shown in Fig. 5. When the operating ring 18 reaches its lowermost position, the needles will occupy the position shown in Fig. 6 which is reversed from that of Figs. 1 and 2. Thereupon the operating ring begins to move upwards, and while loops are being formed by the needles with even numbers, those with 30 odd numbers are raised to the initial position shown in Fig. 2.

Since one group of needles moves upwards while the other moves downwards, the tendency of the fabric to follow the needles will have no 35 effect, and the usual drawing-off mechanism will be sufficient to keep the fabric in position.

In the arrangement shown in Fig. 7 there are two independently moving operating rings 21 and 24, one for each group of needles. The butts 40 of the latter engage in forks 19 and 22 connected respectively to leads 20 and 23 on the two rings, the lever action previously described being thus dispensed with. While the movement of the operating rings 20 and 24 can be controlled so 45 as to produce the same action as that described in connection with Figs. 1 and 2, the action can be varied according to requirements, for instance so that one group of needles remains stationary while the other is operated.

Figs. 8—11 illustrate such an action. In Fig. 8 the needles with odd numbers are about to descend and will do so while the needles with even numbers remain stationary in their lowermost positions. When both sets of needles are 55

level as shown in Fig. 9, the needles with even numbers will be raised, as shown in Fig. 10, while the needles with odd numbers remain stationary, and when the needles with even numbers again arrive in the lowermost position, as shown in Fig. 11, the cycle of operations is repeated.

In the illustrated arrangements vertically operating latch needles are employed, but bearded needles can be operated in the same manner. The arrangement is also suitable for horizontally operating needles as well as for machines wherein both vertically and horizontally operating needles are employed at the same time.

15 I claim:

1. In a circular warp knitting machine, the combination with a needle cylinder and with needles arranged in tricks in said cylinder, of a rocking lever operatively engaging each needle, a support whereon each lever is fulcrumed, an operating ring, and arms on said ring pivotally

connected to the different levers for rocking the latter, adjacent levers having their pivotal connection with the arms situated at opposite sides of the support so as to be rocked in opposite directions.

5 2. In a circular warp knitting machine, the combination with a needle cylinder and with needles arranged in tricks in said cylinder, of two independently movable operating rings for said needles, adjacent needles being connected 10 to different rings.

3. A circular warp knitting machine comprising a needle cylinder, needles carried thereby, the needles being divided into two groups, the needles of one group being intercalated with the 15 needles of the other group, all of said needles being operated simultaneously, but the needles of one group being operated out of phase with the needles of the other group.
